UNITED STATES PATENT OFFICE.

JOSEPH S. DUNCAN, OF CHICAGO, ILLINOIS, ASSIGNOR TO ADDRESSOGRAPH COMPANY, OF CHICAGO, ILLINOIS, A CORPORATION OF ILLINOIS.

TYPE-SETTING MACHINE.

1,063,337.

Specification of Letters Patent.

Patented June 3, 1913.

Application filed July 25, 1910. Serial No. 573,590.

To all whom it may concern:

Be it known that I, JOSEPH S. DUNCAN, a citizen of the United States, residing at Chicago, in the county of Cook and State of Illinois, have invented certain new and useful Improvements in Type-Setting Machines, of which the following is a specification.

This invention relates in general to type setting machines and more particularly to a machine for setting metal type in holders; one of its principal objects being to provide a machine of simple construction adapted for easy and rapid operation by unskilled labor to set up addresses or other subject matter in holders for use in addressing or other printing machines.

Another object is the provision of a machine of this character in which the transferring mechanism shall be so constructed that individual type may be readily transferred from the storage channels of a container to a type holder.

Additional objects and advantages of the invention will become apparent as it is better understood from the following description when taken in connection with the accompanying drawings illustrating a preferred embodiment thereof.

On the drawings, Figure 1 is an end elevation of a machine embodying my invention, certain parts being shown in section. Fig. 2 is a front elevation thereof; and Fig. 3 is an enlarged detail of a portion of the carriage registering and locking teeth. Fig. 4 is a detail view showing the working end of the type setter and the groove in which it works. Fig. 5 is an enlarged fragmentary view showing the relative arrangement and the connection between the key lever and the ejector lever.

Referring to the drawings, 4 is a main frame forming a support for the operative parts of the machine and having a bed 5 in an inclined position thereon, and provided on its forward face with a plurality of parallel type channels 6. Each channel is open at its upper end for the reception of the type, and has one side 7 bent inwardly at its outer edge to prevent the type from being dislodged until the type reaches the lower end of the channel. The lower ends of the channels are sufficiently closed by a strip 8 to prevent the type from dropping out of the channels, and the rear wall of

each channel adjacent the lower end thereof, is provided with an opening 9 through which an ejector, hereinafter described, is adapted to be operated to discharge the type from the channels during the transferring operation.

A carriage is adapted to travel back and forth below the channels and carry a holder to receive the type and the transferring mechanism for discharging the type into said holder. The carriage travels on three tracks, one of which, 10, is preferably arranged substantially at a right angle to the face of the bed 5 and at the bottom of the frame 4. A bar 11 is fastened to the main frame preferably at an inclination corresponding to that of the bed, and a channel plate 12 is fastened to the lower edge of the bar 11 and extends substantially parallel to the track 10. The channel plate 12 projects in front of the bar 11 sufficiently to form a track 12' and the underface of the channel plate 12 is recessed to form another track 15'.

The movable carriage comprises a frame 13 upon which are mounted the rollers 14 adapted to travel upon the track 12', the rollers 15 which travel in the channel track 15', the roller 16 which travels on the forward face of the track 10, and the roller 17 which travels on the rear face of the track 10 and is carried by a bar 18 extending rearward from the carriage frame. These rollers, 14, 15, 16 and 17, support and guide the carriage frame in its movements back and forth on the track adjacent the type channels.

The movable carriage is provided with a relatively movable frame 21 adapted to receive and hold a type holder 24 provided with a plurality of grooves 25 into which the type are transferred from the channels. The type holder may be of any preferred construction, preferably having a plurality of type grooves, of such a character that it may be employed in connection with an addressing or printing machine to carry the address or other printing form for printing envelopes or other matter. This type holder is secured in place between end stops 22 and 23 by means of a latch 26 which is pivoted at 27 upon the type holder frame 21 and is held in operative or inoperative position by a tension spring 28 attached at one end to the latch and at its other end to

a pin 29 on the frame 21. The latch is arranged to engage the holder and secure it in place on the frame 21 between the strips 22 and 23.

5 The type holder 24 is carried in front of and below the type channels 6, but the upper end of the type holder is located opposite the bar 8 at the lower ends of the type channels. In order to position the type holder 10 for the reception of type in any particular groove therein, I have provided mechanism for locking the type holder frame 21 in proper position on the carriage. This mechanism comprises a latch 30 pivoted at 15 31 on the carriage frame and extending above the type holder frame which is provided at its upper end and at one side of the type holder, with a series of serrations 32 with which the outer end of the latch 30 20 is adapted to engage. The latch is normally held in engagement with one of the serrations by an expansion spring 33. When it is desired to adjust the holder relatively to the carriage, the thumb-piece 34 on the 25 latch 30, is pressed against the force of the spring 33 to raise the outer end of the latch out of engagement with a serration. The frame 21 carrying the type holder may then be adjusted on the rods 19 and 20 of the 30 carriage frame 13 and on which the type holder frame 21 is mounted. When the type holder frame has been adjusted to bring the type holder in position with a groove therein registering with the transferring mechanism, 35 the thumb-piece is released and the latch 30 thereupon engages a serration and thereafter holds the type holder frame 21 in its adjusted position on the carriage frame and with the desired groove of the type holder 40 in operative relation to the transferring mechanism.

In transferring type from one of the type channels 6 to the type holder 24, it is necessary that the type be ejected from the front 45 of the channel and at the lower end thereof, and to this end I have provided an ejector 35 mounted to reciprocate in bearings 36 on the carriage frame back of the channels, the ejector being disposed to aline with the 50 openings 9 in the rear of the channels. To actuate the ejector, a lever 37 is pivoted at 38 on the carriage frame and is connected to the ejector by a pin 39 projecting laterally therefrom and engaging in an open top bearing 40 secured upon the upper face of the ejector and permitting a limited adjustability of the lever 37 relatively to the ejector 35. A guide plate 41 is secured to the frame outside the lever 37 to guide it in its backward and forward movements. A tension 60 spring 42 connected at 43 to the lower end of the lever 37 and at 44 to the carriage frame, normally retains the ejector in its inoperative position, as shown in Fig. 1.

65 The ejector lever 37 is operated by means

of a key or type lever 45 pivoted to the carriage frame at 46 and carrying at its outer end an operating handle 47. The lower end of the lever 37 is provided with a beveled lug 48 with which a companion lug 49 secured to the key lever 45 is adapted to cooperate upon downward movement of the key lever to rock the lever 37 on its pivot, whereby the ejector is projected forward through the opening 9 in the rear wall of 70 one of the type channels 6 to force a type outwardly from the channel. A tension spring 50 is secured at one end to a bar 51 projecting downwardly from the lever 45, and at its other end to the carriage frame 7, 75 and its adapted to normally retain the type lever in inoperative position, as shown in Fig. 1.

In order that the ejector may be positioned directly behind the opening 9 in the type channel from which it is desired to eject a type, and in order that the carriage may be held securely in register with the type channel during the transferring operation, there is secured to the lower edge of 80 the bed 5, a bar 52, shown on an enlarged scale in Fig. 3, provided with a series of rearwardly projecting teeth 53. The upper end of the lever 37 is adapted upon its forward movement to slide between two adjacent teeth. The outer ends of the teeth are sharpened and the inner edge of the lever 37 is beveled as at 54 so that the lever will readily enter between two of the teeth when the key lever 45 is operated, and securely hold the carriage in proper registration with the type channel from which a type is to be taken.

The type designated generally 55, is pushed out of the channel by the ejector to a 105 position directly over the upper end of the registered groove in the type holder 24, and in order to push it down into the groove in the holder I have provided a type setter 56 which is pivoted at 31 and extends above the 110 type which is ready to be pushed into the holder.

The outer end 56' of the type setter is bent rearwardly to afford a flat surface to engage with the type to be inserted in the holder. The carriage frame is provided with a transfer pocket 57 into which the type are pushed from the channel by the ejector through an opening 57' in the bottom of the pocket. The flat end 56' of the type setter is normally located in the pocket above the opening 57'. Immediately after the ejector pushes the type into the pocket the type setter pushes it down from the pocket into the holder groove. Thereafter each type inserted in a groove pushes the type ahead of it in the groove farther along. A tension spring 58 attached at one end to the type setter and at its other end to the carriage frame normally maintains the setter in elevated position.

tion, as shown in Fig. 2; while a stop 58' on the frame limits the upward movement of the type setter.

The type setter is operated by the key lever 45 and it has a lost motion connection with a bar 60 which is pivoted at 59 to the key lever. This bar has a longitudinal slot 61 near its upper end and a screw 62 extends through this slot and is screwed into the type setter 56, whereby a lost motion connection is provided between the type setter and the key lever, which gives the transerrer time to push the type out of the channel before the setter operates. When the key lever has been depressed until a type has been ejected to position above a groove in the holder, the upper end of the slot 61 engages with the screw 62 and depresses the outer end of the type setter, thereby forcing the type down into the groove in the holder. As additional type are added to a groove the type setter forces them farther into the holder longitudinally of the groove.

In the operation of my device an empty holder is positioned on the carriage with the groove which it is desired to fill first in register with the ejector and the type setter. The carriage is then moved along the frame until the ejector is substantially in alignment with the particular type which it is desired to transfer from the channel to the holder. The key lever 45 is then depressed and the upper end of the lever 37 is moved between the teeth 53 to insure alignment of the ejector with the opening in the rear of the type channel and to lock the carriage against movement during the transferring operation. As the key lever is further depressed the ejector pushes a type out from the front of the channel into position beneath the type setter, whereupon continued downward movement of the key lever will actuate the setter to force the type into the groove. When the key lever is released the springs 42 and 50 will return the parts to normal position. The carriage may then be adjusted longitudinally of the frame to bring the ejector into alignment with the type which is next desired to be added to the groove. When the required line has been set up in one groove the type holder may be adjusted on the carriage to bring the next groove into alignment with the type setter.

While I have shown and described a preferred embodiment of my invention it will be obvious that various changes may be resorted to in its construction without departing from the principle of the invention or sacrificing any of the material advantages thereof.

What I desire to claim is:

1. In a type setting machine, the combination of a series of channels, a series of teeth fixed with respect to the channels and projecting rearwardly therefrom, a carriage adapted to travel adjacent the channels, an ejector slidably mounted on said carriage behind said channels, a lever pivoted on the carriage and operatively connected with the ejector, said lever being adapted to engage with the teeth at the rear of the channels to position the carriage during the ejecting operation, a beveled lug secured to the lower end of said lever, a key lever mounted on the carriage, a beveled lug on said key lever adapted to engage with and actuate said ejector lever and means for returning said levers independently to normal position.
2. In a type setting machine, the combination of a series of channels, a series of teeth fixed with respect to the channels and projecting rearwardly therefrom, a carriage adapted to travel adjacent to and in front of the channels, an ejector slidably mounted on said carriage behind said channels, a lever pivoted on the carriage and operatively connected with the ejector, said lever being adapted to engage with the teeth at the rear of the channels to position the carriage during the ejecting operation, a beveled lug secured to the lower end of said lever, a key lever mounted on the carriage, a beveled lug on said key lever adapted to engage with and actuate said ejector lever, a holder adjustably mounted on said carriage, and means connected with said key lever to be actuated thereby when said key lever approaches the limit of its movement for positioning an ejected type in said holder.
3. In a type setting machine, the combination of a plurality of type channels, a carriage adapted to travel adjacent said channels, a type holder removably mounted on the carriage and having one or more type grooves, means for adjusting the holder on the carriage, an ejector adapted to push a type outward from said channels, means for positioning said carriage with a groove in the type holder in alignment with one of said channels during the ejecting operation, a type setter adapted to position an ejected type in the holder, and a key lever mounted on the carriage to actuate the carriage positioning means, the ejector and the type setter.
4. In a type setting machine, the combination of a frame provided with a series of type channels closed at their lower ends and provided with an opening in their rear walls near the bottom thereof, a carriage adapted to travel adjacent said type channels, a transfer pocket mounted on said carriage, a carriage lock, an ejector for introducing the type into said pocket, a type holder, a type setter for positioning the type in the holder, and means pivotally mounted on the carriage for operating successively said carriage lock, ejector and type setter.
5. In a type setting machine, the combination of a series of channels provided with

openings in their rear walls near the lower ends thereof, said channels being closed at their lower ends to prevent the escape of type, a carriage, a transfer pocket mounted thereon, a frame slidably mounted on said carriage, a type holder detachably secured to said frame, means for retaining said frame in adjusted position on the carriage, means for locking the carriage relatively to a type channel, means for forcing the lower type in a channel forwardly out of the channel and into said pocket in alignment with a groove in the type holder, and means for removing the type from said pocket and positioning the type in a groove in the holder.

6. In a type setting machine, the combination of a series of type holding channels provided at their lower ends with ejector receiving openings, a carriage mounted to travel transversely of said channels, a frame adjustably mounted on said carriage and provided with upwardly projecting serrations, a latch mounted on said frame and adapted to normally engage said serrations to lock the frame in adjusted position, a type holder removably mounted on said frame in front of said type channels, a transfer pocket, a transerrer for transferring type from said channels to said pocket, a type positioner for removing type from said pocket and positioning the same in said holder, and operating means for successively actuating said transerrer and said positioning device.

7. In a type setting machine, the combination of a frame provided with a series of type channels closed at their lower ends and provided with an opening in their rear walls near the bottom thereof, a carriage adapted to travel adjacent said type channels, a locking member pivotally mounted on the carriage and adapted to engage the frame to lock the carriage in desired position, an ejector loosely connected to said locking member for ejecting type from the channels, a type setter for positioning the type on the carriage, and means for operating successively said locking member, ejector and type setter.

8. In a type setting machine, the combination of a frame provided with a series of type channels closed at their lower ends and having an opening in their rear walls near the bottom thereof, a carriage adapted to travel adjacent said type channels, a locking lever pivotally mounted on the carriage and adapted to engage the said frame to lock the carriage in desired position, an ejector slidably mounted upon the said carriage and having a sliding and pivotal connection with the said locking lever, a type setter for positioning the type on the carriage, and means pivotally mounted upon the carriage for operating successively the carriage, lock, ejector and type setter.

JOSEPH S. DUNCAN.
